R. D. CORKE

SHARPENING BLOCK FOR RACING SKATES

Filed Dec. 2, 1926

Inventor

Richard D. Corke

By his Attorney

Daniel L. Morris

UNITED STATES PATENT OFFICE.

RICHARD D. CORKE, OF YONKERS, NEW YORK.

SHARPENING BLOCK FOR RACING SKATES.

Application filed December 2, 1926. Serial No. 152,236.

The present invention relates to improvements in clamping devices and more particularly in clamping devices adapted to serve as sharpening blocks for skates and to maintain the skates securely in position while being sharpened.

Among the principal objects which the invention has in view are: To provide a device of this class particularly adapted to 10 clamp tight the blades of the skates without touching the other parts thereof or subjecting them to any clamping action; to provide such a device which shall insure the exact positioning of the skates, thus obviating 15 the possibility of setting the skates at incorrect angles, while being sharpened; to provide a sturdy strong construction and yet one in which the weight is not excessive; and generally to provide improvements 20 in sharpening blocks of this character with a view to simplifying and cheapening the construction and rendering the same more efficient and reliable in service.

With the above and other objects in view 25 the invention further consists in the arrangements of parts and details of construction more specifically pointed out in the following description of the accompanying drawings forming a part of this specification.

In the drawings:

Figure 1 is a perspective view of a device illustrating the invention showing a skate clamped in position to be sharpened.

Figure 2 is an end view of this device showing two skates clamped in position.

By reference to the drawings it will be noted that the device illustrated embodies a circular bar or rod, 10, composed of brass or similar metal and extending in horizontal, 40 longitudinal direction. On this bar the clamping members are adapted to be slidably and adjustably positioned, the bar serving to maintain them in accurate alinement. Each clamping member comprises a frame portion 11, and a hub portion 12, these portions being integrally formed and connected together as by means of a yoke composed of radiating arms 13. The top portion of

50 the hub 12 is split at 14 and the two portions of the hub thus defined merge into curved substantially semi-circular jaw members 15 which cooperate with similar jaw members 16 formed integrally as part of the frame 11. By means of this construction substantially circular recesses 17 are provided in which

are adapted to be positioned the tubes 18 of the skates. Thus it will be seen that the clamping action of the jaws is exerted only upon the blades 19 of the skates and the tubes and the other portions of the skates are not affected thereby.

In combination with this construction are provided means for forcing the jaws together so that they may hold the skates securely in position, and, to this end, bolts 20, extending transversely through the clamping members are employed. These bolts are provided with winged nuts, 21, which when tightened, serve to force the jaws together and when loosened allow them to spread apart because of the resiliency thereof.

The heel clamping members are preferably provided with extensions, 22, as shown in Figure 1. This results in a construction 75 by which racing skates of all sorts may be securely clamped, regardless of shortness of heel.

From the above it will be apparent that the skates are positioned in the clamping members by loosening the winged nuts 21 which allow the jaws to spread apart after which the skates are disposed therein with the tubes positioned in the circular recesses in the manner shown in the drawings. Thus, 85 when the winged nuts are tightened, the jaws clamp the skates securely in position but only act upon the blades of the skates and do not clamp the other parts thereof. When the wing nuts are tightened, the hub jaws 90 are pulled toward one another so that the hubs are placed under tension on the bar 10 and the clamping members locked in position. It will be seen also that by means of this construction the skates are secured in 95 substantially horizontal positions and there is no danger of their being set at incorrect angles. This provides a construction, therefore, in which the skates are sharpened absolutely correctly.

This device may be used with all makes and sizes of racing skates, it being only necessary to slide the clamping members on the bar 10 in order to adjust the distance between them.

Although I do not confine myself to any particular material for the clamping members, I have found that an aluminum alloy possesses peculiar utility when used for the purpose. This material is both strong and tough, is impervious to water and does not rust or warp. Although it provides a metal

construction it is withal very light and does not exceed in weight to any great extent the wooden constructions now used.

Although I have described in some detail the preferred construction, I do not desire to confine myself to the exact details thereof except as necessitated by the state of the prior art and the scope of the appended claim.

10 I claim:

A device of the class described comprising a longitudinally extending bar and a plurality of clamping members slidably mount-

ed thereon, each of said clamping members comprising a hub portion around the bar, 15 a frame portion, means connecting the frame and hub, resilient clamping jaws carried by the frame and hub, and means for pulling the jaws of the frame and hub toward each other whereby the hub is put under tension 20 on the bar.

In testimony whereof, I have signed my name to this specification this eighth day of November, 1926.

RICHARD D. CORKE.
